UNITED STATES PATENT OFFICE.

NICHOLAS GOROD, OF BROOKLYN, NEW YORK.

DESIGN FOR A RING.

52,790.

Specification for Design. Patented Dec. 24, 1918.

Application filed May 9, 1918. Serial No. 233,599. Term of patent 7 years.

To all whom it may concern:

Be it known that I, NICHOLAS GOROD, a citizen of the United States, residing at New York city, in the borough of Brooklyn and State of New York, have invented a new, original, and ornamental Design for Rings, of which the following is a specification, reference being had to the accompanying drawing, forming part thereof.

Figure 1 is a perspective view showing one face of a ring embodying my new design and,

Fig. 2 is a similar view showing the other side of the ring.

I claim:

The ornamental design for a ring as shown and described.

NICHOLAS GOROD.

Witnesses:

FRANK M. ASHLEY,
CHAS. E. WARD.
